UNITED STATES PATENT OFFICE.

ARTHUR S. BRETHERTON, OF CLEVELAND, OHIO.

PARCEL-CARRIER.

No. 840,746.

Specification of Letters Patent.

Patented Jan. 8, 1907.

Application filed September 25, 1906. Serial No. 336,175.

To all whom it may concern:

Be it known that I, ARTHUR S. BRETHERTON, a citizen of the United States, residing at Cleveland, in the county of Cuyahoga and 5 State of Ohio, have invented new and useful Improvements in Parcel-Carriers, of which the following is a specification.

This invention relates to improvements in apparatus for the rapid conveyance or transportation of small packages or parcels; and 10 it consists in the novel construction, combination, and arrangement of devices herein-after described and claimed.

The object of the invention is to provide a 15 simple and practical electrically-operated apparatus of this character which will be entirely automatic in its operation.

Another object of the invention is to provide an electrically-propelled carrier of the 20 character described having combined track and conductor wheels which run both upon track-rails and in engagement with electrical conductor wires or rails.

Further objects and advantages of the invention, as well as the structural features by 25 means of which they are attained, will be made clear by an examination of the following specification, taken in connection with the accompanying drawings, in which—

30 Figure 1 is a side elevation of the improved package-carrier or transportation apparatus, and Fig. 2 is a cross-sectional view through the same.

In the practice of my invention I provide a 35 car or carrier 1 of suitable form and construction mounted upon peripherally-grooved wheels 2, which run upon track-rails 3, and also engage wires or rails 4, which latter are arranged above the track-rails 3. The track- 40 rails 3 are preferably of the usual T form with a half-round top, as shown, and the elements 4 are preferably in the form of heavy wires supported by hangers 5 from suitable supports 6. One or both of the 45 wires 4 may be used as conductors for conveying an electric current to the motor within the carrier or car 1, and they further serve to steady the car and retain it upon the track-rails, the grooves 7 in the peripheries 50 of the wheels 2 being sufficiently deep to effect this result. One or both of the track-rails 3 may also be used as electrical conductors.

While the apparatus may be mounted close to the surface of the ground or in an under- 55 ground conduit or subway, I preferably

mount it in an elevated position by securing the track-rails 3 upon cross-bars 8, which are suitably secured to posts or poles 9, arranged at suitable intervals. The supports 6 are in the form of cross-bars suitably secured to the 60 posts 9 above the cross-bars 8, as shown in Fig. 2. I also preferably arrange one pair of the track-rails 3 upon each side of the post, so that one may be used for the car for its movement in one direction and the other for 65 its return.

The car or carrier 1 is preferably constructed of metal and of substantially cylindrical form, its top being slightly flattened and its ends tapered to points, as shown at 70 10. The interior of the car may be divided into suitable compartments, and suitable doors 11 may be provided upon the flattened top of the car-body, so as to permit of access to such compartments. An electric motor 75 12 of any suitable form may be disposed in one of these compartments and may be mounted either directly upon the axle of one pair of the wheels 2 or otherwise suitably mounted and geared to one of the axles. It 80 will be observed that the wheels 2 are fixed upon the projecting outer ends of transverse axles or shafts 13, which rotate in suitable bearings 14, arranged at opposite points in the car-body.

85 Any suitable means may be provided for turning on and off and varying the supply of the electric current to the motor 12; but, as illustrated, this is effected by four levers 15, 16, 17, and 18, which have their lower ends 90 projecting through and movable in slots or openings in the bottom of the car and their upper ends suitably connected to switches or other devices (not shown) by means of which the desired effect may be produced. 95 When the lever 15 is shifted, the motor starts at half speed. When the lever 16 is shifted, the car travels at full speed. When the lever 17 is shifted, the car slows to half speed, and when the lever 18 is shifted the supply of current is cut off from the motor and the car stops. The stopping of the car may be effected in any desired manner, but preferably by an uphill section of the track at the end of the line. The lever 15 is operated manually 105 when the car is started, and the levers 16, 17, and 18 are successively operated by trip devices 19, arranged at suitable intervals along the track, so that the car is automatically controlled from the time it starts until the 110

time it reaches its destination. These trip devices are here shown in the form of metal plates secured upon the cross bars or supports 8 for the track-rail and having their upper edges formed with notches 20, which align with certain of said levers. When the car passes one of these trip-plates 19, which has no space in line with one of its levers, such lever will strike the plate and be shifted, as will be readily understood.

The current is taken from a power plant (not shown) and conveyed to the motor in the car by the copper wire 4, through the wheels 7, and the rails 3, which form the return.

The construction, operation, and advantages of the invention will be readily understood from the foregoing description, taken in connection with the accompanying drawings.

Having thus described my invention, what I claim as new, and desire to secure by Letters Patent, is—

1. The combination with track-rails and wires arranged above the same, one of said wires serving as an electric conductor, of a carrier, an electric motor thereon, an axle driven by said motor, and grooved wheels fixed upon said axle and engaged with said

track-rails and said wires, substantially as 30 shown and described.

2. The combination with track-rails and wires arranged above the same, one of said wires serving as an electric conductor, of a carrier, an electric motor thereon, an axle 35 driven by said motor, grooved wheels fixed upon said axle to run upon said track-rails and engage said wires, and means for automatically controlling the supply of an electric current to the motor.

3. The combination with track-rails and wires arranged above the same, one of said wires serving as an electric conductor, of a carrier, an electric motor thereon, an axle driven by said motor, grooved wheels fixed 45 upon said axle to run upon said track-rails and engage said wires, a motor-controlling device upon said carrier and a trip arranged adjacent to the track-rails for actuating said device.

In testimony whereof I have hereunto set my hand in the presence of two subscribing witnesses.

ARTHUR S. BRETHERTON.
